UNITED STATES PATENT OFFICE.

JUDSON A. CARR, OF MONMOUTH, ILLINOIS.

DEVICE FOR OPENING FURNACE-DOORS.

SPECIFICATION forming part of Letters Patent No. 252,183, dated January 10, 1882.

Application filed May 17, 1881. (No model.)

To all whom it may concern:

Be it known that I, JUDSON A. CARR, of Monmouth, Warren county, Illinois, have invented a new and Improved Device for Opening Furnace-Doors, of which the following is a specification.

The object of this invention is to provide a more simple, inexpensive, convenient, and effective device for opening and holding open 10 furnace-doors when it is desired to replenish the fires.

The invention is especially adapted to boiler fire-boxes and house-heating furnaces; and it consists of a combined treadle-lever and connecting-rods connected with the furnace-door, which open upward in such a manner that the operator can open the door by pressure upon 15 the treadle and close the door by removing his foot from the treadle.

20 In the drawings, Figure 1 is a front elevation, showing the device applied to a furnace-door. Fig. 2 is a side elevation of the same with part b:oken away to exhibit other parts.

Similar letters of reference indicate corresponding parts.

In the drawings, A represents a boiler or other fire-box or furnace; B, the door-frame set therein, and C the door, hinged at a so as to open vertically. A standard, D, having a 25 hook, b, formed on its upper end, projects upward from the door-frame B, and on this hook b is suspended a horizontal lever, E, one end of which is connected by a rod, F, with a ring or eye, c, on the door C, while the other end is 30 connected with a treadle, G, by a rod, H, the opposite end of the treadle G being secured to the floor L by a staple or ring, K.

The weight of the door C is designed to overbalance the weight of the treadle G and rod H, so that said door C shall remain closed 40 when there is no pressure on the said treadle G.

To open the door the operator places a foot upon the treadle G, as shown in Fig. 2, whereby the treadle G is brought down in a horizontal position, and the door C also in an open horizontal 45 position, as shown.

I am aware that it is not new to hold open a furnace-door by a weighted cord passing over pulleys, or by a treadle on an arm which passes beneath the door, or by a treadle connected by levers with a spiral shaft arranged under the foot-board; but 50

What I do claim as new and of my invention is—

The combination, with the standard D, secured at its lower end to the door-frame B and provided at its upper end with the hook b, of the lever E, suspended from said hook, rod H, secured at its upper end to one end of the lever E and attached at its lower end to the free 55 end of the treadle, treadle G, pivoted to the floor, and rod F, secured at its upper end to the opposite end of the lever E and at its lower end to the eye c of the door C, opening upwardly and overbalancing the weight of the 60 treadle and rod H, whereby the furnace-door can readily be opened by the operator by placing his foot on the treadle and automatically closed by removing his foot therefrom, substantially as described.

JUDSON A. CARR.
